Application filed October 24, 1890. Serial No. 369,234. Term of patent 3 $\frac{1}{4}$ years.

To all whom it may concern:

Be it known that I, EDWIN W. LAWSON, a citizen of the United States, residing at Elgin, in the county of Kane and State of Illinois, have invented a new and original Design for Badges, of which the following is a specification.

My design consists, essentially, of an ornamental pin in the form of a shield, having 10 the representation of an open book, a pair of dumb-bells, and a pair of Indian clubs thereon.

In the accompanying drawings, illustrating my invention, Figure 1 is a representation of 15 my badge as designed for a parent or general association or the grand chapter of an association, and Fig. 2 is a representation of my badge as designed for a local or sub chapter.

In the drawings, A indicates a badge of 20 shield-like contour, having any usual or convenient means of attachment, such as a pin or clasp.

Upon the face of the badge is formed, in any suitable way, the representation of an open book B, a pair of Indian clubs C C, and 25 a pair of dumb-bells D D. E is a panel or space surmounting these symbols.

While I have described my invention as a badge, the word is to be taken in its largest signification.

Having thus described my invention, what I claim as new, and desire to secure by Letters Patent, is—

The design for a badge or emblem herein described and shown, which consists in an 35 ornamental shield having upon its outer face the representation of an open book, a pair of dumb-bells, and a pair of Indian clubs, substantially as shown.

In testimony that I claim the foregoing as 40 my own I have hereto affixed my signature in presence of two witnesses.

EDWIN W. LAWSON.
